UNITED STATES PATENT OFFICE.

JEAN BAPTISTE DOMINIQUE LÉON CHARDARD, OF PARIS, FRANCE.

RADIATOR CONSTRUCTION.

1,416,944.

Specification of Letters Patent. Patented May 23, 1922.

Application filed September 20, 1919. Serial No. 325,205.

To all whom it may concern:

Be it known that I, JEAN BAPTISTE DOMINIQUE LÉON CHARDARD, citizen of the Republic of France, and resident of Paris, France, (post-office address 41 Rue Ribeira,) have invented a new and useful Radiator Construction, which improvements are fully set forth in the following specification.

This invention relates to a radiator for 10 motor and other vehicles, chiefly characterized by very thin parallel layers of water, of any desired shape, either rectilinear or concentric, being formed in front of the vehicle, between which can circulate the air 15 produced by the movement of the vehicle or by a fan, the number of such layers being capable of variation at the will of the driver, to suit the atmospheric conditions.

In these conditions it is possible to stand 20 ardize the apparatus.

In order to make the following explanation as clear as possible, the accompanying drawing shows by way of example a radiator according to this invention.

25 In the said drawing,

Figure 1 is a diagram graphically illustrating the theory of construction of the new radiator;

Figure 2 is a front elevation of the radi- 30 ator;

Figure 3 a central vertical cross-section;

Figure 4 a cross-section of a modified method of connecting the interchangeable radiator elements to the main collector;

35 Figures 5 and 6 show a second modified construction that can be used when the space required for erecting is limited;

Figure 7 is a modified construction in 40 which the locking of the elements can be effected from the front of the radiator.

When any existing radiators are considered, it will be found that the length of the fixed or detachable layers or blades varies in each type of radiator. Some of them, as 45 shown in Figure 1, have for instance a length A of elements, others a length B, others a length C, others a length D, etc., each length corresponding to a given radiating surface. It is obvious that in these conditions, all the radiators have a common surface corresponding to the cross-hatched surface A; others, in addition to the common cross-hatched surface A, have another dotted 50 surface corresponding to the difference be-

tween B and A, and so on. It will be seen 55 therefore that if elements are produced, with which the radiating surface A can be obtained, these elements will be applicable to any radiators. In order to pass from the radiators A to the radiators B, it will be 60 sufficient to add to the original elements a certain number of elements. The same will be the case in order to pass from the radiators B to the radiators C. It will be seen, 65 therefore, that by producing unit elements, either rectilinear or circular or of any other suitable shape, parallel to each other, it will be possible with a number x of these elements, to obtain a radiating surface suitable for any existing radiators, without changing 70 the outer dimensions of the apparatus. By adding one, two or three of these unit elements, the second group of radiators B will be obtained, and radiators of this kind will be formed, again without modifying the 75 dimensions of the apparatus, and so on as regards the others.

According to the characteristic feature of the invention, cooling elements are therefore formed which must have the following properties:

1. These elements must be separately detachable and interchangeable.

2. When one of these elements is removed, the radiator must be able to continue to 85 work, the connections of the element to the main collector being closed by plugs. It will be seen that owing to this arrangement, it will be possible to effect the necessary 90 repairs to a damaged element, without putting the radiator out of action.

3. All the elements of the series are the same for all existing types of radiators. If therefore an element is completely destroyed and requires replacing, it will be sufficient 95 to buy an element of the type to which the destroyed element belongs, in order to replace it at once.

4. Detachability of the elements makes it possible to vary the cooling surface to suit 100 the temperature.

5. This detachability also renders possible the cleaning of the cooling surface.

By way of example of a practical construction of these standardized elements, Figures 2 and 3 show a radiator with concentric flat elements. It must be however understood that, instead of using concentric

flat layers or blades covered with ribs, the elements could be constituted by corrugated sheet metal, by tubes with or without ribs; by honeycombs etc., in short by any systems 5 at present used.

- As shown in the drawing, all the constituent elements of the radiator are detachable; all these elements are of circular shape and concentric; each of them is substantially 10 constituted by a chamber *a* flattened in cross-section so as to form a layer of water. The chamber *a* is provided outside with cooling ribs *b* increasing the surface of contact of the chamber *a* with the air.
- 15 Circulation of the water to be cooled in the radiator, takes place in the following manner:

Behind the chambers *a* is arranged a vertical column *c* forming a collector, which is 20 common to all of the radiator elements or chambers and which communicates with the headers *d* and *e*. The central portion of this column *c* is closed, as will be understood from Fig. 3, the result being that there are 25 formed, in effect, two independent or separate collectors, one above and the other below the aforesaid closed central portion. Each element or chamber *a* is connected laterally by a conduit *f* to the upper collector section, and by a similar conduit *f'* to the lower collector section; the points of connection of both conduits to the corresponding collector sections being arranged in staggered relation, as indicated in Fig. 2.

30 It will be seen that each element or chamber *a* comprises an inlet for the water to be cooled and an outlet for the cooled water. In the centre is arranged either the head light *g*, or additional elements or simple ribs.

35 As already stated, all the elements are detachable. It is therefore possible to remove any desired number of elements *a* or to put in place any desired number of these elements, according to the power of the engine.

40 The fixing of the elements *a* is effected in the following manner: each element *a* is provided, at the top and at the bottom, with conical branches or nozzles which fit in and project through casings or sockets *h* of the 45 corresponding shape provided in the collector sections or collectors *c*. A nut *i* screwed onto the projecting end of each nozzle behind the corresponding collector, ensures a tight joint. It goes without saying that the 50 socket, on the one hand, and the conical nozzle, on the other hand, are provided with openings which exactly register with each other after the parts have been assembled.

When an element has been removed by 55 simply unscrewing its nuts *i*, the openings are closed by conical plugs tightened by means of the same nuts.

The erecting of the collector column is effected by riveting it between the upper or 60 hot water tank or header *d* and the lower or

cold water tank or header *e*, communication between the hot and cold water tanks being prevented by the closed central portion of the column, as previously stated.

As has been just seen, the radiator comprises 70 a series of cooling elements formed by smooth or corrugated layers or units, by tubes, by honeycombs, etc., arranged parallel to each other and having any suitable shape: straight, circular, elliptical, etc. Each of 75 the said elements can be separately detached from the column or main collector, which is common to all of the elements and which takes the same form for all types of radiators. The said column is riveted at its ends 80 to the hot and cold water tanks, the orifices of communication of each element with the collector sections being closed by means of conical plugs whenever the element is removed.

85 It may happen that in spite of all the precautions taken, the conical nozzles mounted on the various interchangeable elements, fail to coincide very accurately with the sockets of the collector, these parts having, to that end, to be carefully ground to suit the circumstances.

In order to remedy the drawback in question, the following arrangement could be 95 used:

The nozzles of the various interchangeable elements may each be provided with a portion screw-threaded inside or outside, in order to enable a sleeve *A'* (Fig. 4) to be 100 screwed thereon, which sleeve will be always the same for the various elements, thereby insuring the accurate mounting of the parts on the main collector, the grinding of the sleeve and of the corresponding socket *B'* of the collector having been done in a perfect 105 manner once for always.

The taper of the sleeve and that of the socket could be suitably calculated, according as the assembling of the elements would have to be done from the outside or from 110 the inside.

The sleeve having been screwed on the corresponding nozzle of the element to be mounted on the collector, with the interpolation at *j* or *j'* of a suitable packing or joint 115 for the purpose of avoiding leaks, the attachment of the element to the collector will be effected as indicated in the preceding, and each element may be moreover considered as if the nozzle and the sleeve were in one piece. 120 After having introduced the sleeves *A'* into their sockets *B'*, it will be sufficient to tighten the nuts *C'* in order to ensure a tight joint.

If a leak is discovered in one of the elements, it will be sufficient to introduce a screw-driver or a coin into the slot *D'* provided on the back of the sleeve *A'* of each of the two nozzles *T* of the element and to turn it through a quarter of a revolution to 130

the left. The openings of the sleeve will thus cease to register with those of the sockets of the collector, and the element will be therefore completely shut off, without it being necessary to remove it; it will be sufficient to lock again the element by tightening the nut C'.

In the event of the space required for the assembling being limited and making it impossible to introduce from the front of the collector the nozzles provided with their sleeves, the arrangement shown in Figures 5 and 6 will be utilized. The elements are shown in front without the nozzles T being provided with their sleeves, and the latter are screwed on the screwthreaded portion of the said nozzles by introducing the sleeves A' from the back of the collector.

In the case of certain radiators arranged at the back in some types of cars, the cooling elements cannot be withdrawn except in a direction parallel to the collector; the arrangement shown in Figure 6 is then adopted. The nozzle T is arranged in this case parallel to the collector and provided with a boss T' normal to the latter for attachment to the said collector, as in the case of Figure 5.

In the arrangement shown in Figure 7, the locking of the elements can be effected from the front of the radiator. The joints are arranged at j' and j''. The bottom of the socket B' has a rod F which passes through the sleeve A' and the nozzle T, and is screw-threaded at the front end; the locking is effected by the tightening of the nut C' at the front of the element.

It will be readily understood that the various methods of mounting described in the foregoing, are applicable to cooling devices of any engines, whether stationary or mounted on any vehicle, as well as to any temperature exchange devices of whatever kind, for

instance to domestic radiators. They are also particularly applicable to bath heaters. 45

It will be possible, with the various arrangements above described, to vary at will the radiating surface to suit the surrounding temperature. It is possible for instance to shut off according to the season, one, two 50 or more elements by closing the sockets for the purpose.

I claim—

1. A radiator construction, comprising upper and lower headers; a series of detachable radiator elements arranged in nested parallel relation, each pair of adjoining elements being spaced apart to enable the passage of air therebetween; and a vertical collector embodying non-communicating upper and lower parts, one connected to the upper header and the other to the lower header; each radiator element communicating with both collector parts. 55 60

2. A radiator construction comprising upper and lower headers; a collector embodying non-communicating upper and lower parts connected to the corresponding headers; a series of radiator elements arranged in spaced, parallel relation to enable the passage of air between them; each said element consisting of a flattened tube detachably connected at its upper portion with the upper collector part and at its lower portion with the lower collector part and 70 75 communicating with openings in said collector parts at its points of connection thereto; and means for blocking the openings corresponding to any individual radiator element.

3. A radiator construction according to claim 2, in which the several radiator elements take the form of concentric circles. 80
